FINGER RING HOLDER

Lyman G. Hunter, Indianapolis, Ind., assignor to
Herff-Jones Company, a corporation of Indiana

Application March 13, 1951, Serial No. 215,230

1 Claim. (Cl. 206—76)

1

This invention relates to a device for holding finger rings individually, the device being capable of being made in a plurality of holders in an extended length, or in a unitary form to hold a single ring by itself. The invention is herein described in the unitary form wherein the usual round "button" type of holder is employed to be mounted generally on a display board or case having a plush or velvet surface surrounding the holder.

A primary purpose of the present invention is to provide a friction gripping means whereby the shank may be inserted down into a normally closed slot so that the side walls of the slot will yieldingly be separated by the insertion of the ring shank therein, that is between the walls of the slot, in such a manner, that the yielding grip will be maintained over almost an indefinite period of time as opposed to the yielding grip of fibrous materials such as cotton or wool which has heretofore been employed.

There is also the problem involved of not only yieldingly holding the ring by its shank, but doing so in a manner which will not scratch or abrade the material of the shank so that the ring may be removed from the holder and returned thereto innumerable times without any damage to the ring being occasioned.

The structure embodying the invention provides a diametrical slot of considerable width across a cylindrical section of a block, wherein a combination of flat and bowed springs are carried to be separate by resilient padding, the resilient padding being divided by a fold of an over-all covering material.

Many other objects and advantages of the invention will become apparent to those versed in the art in the following description of one particular form of the invention as illustrated in the accompanying drawing, in which

Fig. 1 is a top plan view and partial section of a structure embodying the invention;

Fig. 2 is a vertical transverse section on the line 2—2 in Fig. 1;

Fig. 3 is a view in side elevation of a spring unit;

Fig. 4 is a view in top plan of the spring unit; and

Fig. 5 is a view in end elevation of the spring unit.

A cylindrical length of any suitable material which is substantially rigid, such as wood is employed as the base block 10 of the over-all combination. The block 10 is provided with a diametrical slot 11 thereacross, being defined by the side walls 12 and 13 and the floor 14.

2

As will be noted, Fig. 2, this slot 11 is open at the top side of the block 10 but closed by a rather thin section 15 of the block across its underside, the floor 14 being the top side of this section 15.

5 For most sizes of ring shanks, and particularly where the block 10 is in the cylindrical form as herein described, the transverse width of the slot 11 from wall 12 to wall 13 is substantially or approximately half of the diameter of the block 10.

10 A spring unit or assembly generally designated by the numeral 16, as illustrated in Figs. 3-5 inclusive, is built up from a straight, flat, planar leaf spring 17 having an over-all length equal to the length of either side wall 12 or 13, and preferably slightly longer as indicated in Fig. 1. The width of the spring member 17 is made to be somewhat less than the height of the walls 12 and 13 as indicated in Fig. 2.

15 On the back side of the straight leaf spring 17, there is mounted a bow spring 18, secured by its central portion to the central portion of the leaf spring 17, by any suitable means such as riveting or spot welding, herein shown as being welded. The extreme outer ends of the bow spring 18 are curved reversely toward the ends of the leaf spring 17, the over-all length of the bow spring 18 from end to end being slightly less than the over-all length of the leaf spring 17.

20 One of these spring units 16 is placed against each of the walls 12 and 13 respectively to have the bow spring 18 adjacent the wall in each instance, and the flat leaf spring 17 removed therefrom so that the flat springs 17 are in opposition one with the other. The transverse dimensions of these units 16 are such that normally the distance between the leaf springs 17 is a major part of the distance between the two walls 12 and 13.

25 Between these two leaf springs 17 in each instance, there is inserted a resilient packing 19 such as cotton, and this packing 19 is carried upwardly and over the spring unit 16 in each instance to lap over on the top face 20 of the block 10 on each side of the slot 11.

30 A retainer covering 21 preferably made out of a cloth fabric is folded diametrically to provide the fold 22 thereacross, and this fold 22 is carried down centrally between the packing 19 to have the lower end of that fold 22 preferably glued to the floor 14 centrally between the leaf springs 17. The covering 21 is carried over the packing 19 in opposite directions of the fold 22 and brought down around the outer side of the block 10 and secured thereto circumferentially therearound by any suitable means, such as by gluing. The covering 21 is continued across the

ends of the slot 11 so that externally, the cylindrical shape of the entire combination is maintained.

The cotton packing 19 is so selected in quantity that it will normally maintain the fold 22 in closed condition as indicated in Figs. 1 and 2 so that the fold has to be forcibly separated against not only the yielding resistance of the packing 19 initially, but also in turn against the yielding resistance of the spring units 16 spaced from the fold 22 by the packing 19. That is the packing 19 serves initially to yieldingly receive the shank of a ring within the fold 22 to have that packing conform itself to the general shape of the shank, and also to tend to press within the shank as a means for releasably securing the shank within the fold. The packing 19 however is not sufficient to absorb all of the side pressure required for entering the shank of the ring within the fold 22, so that the cotton 19 in turn has to push outwardly on the two spring units 16 to tend to compress the bow spring 18 against the side walls 12 and 13 of the slot 11 and also tending to bow the leaf spring 17 centrally or at its outer ends depending upon where the shank of the ring is positioned within the fold 22. The flat face of the leaf spring 17 presented toward the packing 19 serves to retain that packing 19 snugly against the fold 22 on the outer sides thereof so as to 30 maintain normal contact or closure of that fold when not in use as having a ring shank carried therein.

The material of the spring unit 16 is made of very light gauge metal so as to be quite resilient. Yet it has sufficient elasticity so as to return to its normal shape as best indicated in Fig. 4 where the padding 19 is returned to close the fold 22 as indicated in Fig. 2, so that some pressure is required to insert the ring shank into that 40 fold 22.

While I have herein shown and described my

invention in the one particular form, it is obvious that structural changes may be embodied without departing from the spirit of the invention, and I therefore do not desire to be limited to that precise form beyond the limitations which may be imposed by the following claim.

I claim:

A finger ring holder having a slot thereacross defined by side walls; a pair of spring units carried in said slot, each of said units comprising a flat leaf spring having a length greater than the outside diameter of said ring, and a bowed leaf spring secured by its central portion to a central portion of said flat spring to have free ends turned from said flat spring, said ends being spaced apart a distance approaching the length of the flat spring, and said flat springs being positioned one adjacent the other with the bow springs thereof directed by said ends toward the walls defining said slot; and a resilient packing overlying said holder and springs and extending compressibly within said slot between said flat springs, said packing entering between said flat springs by a fold opening from the top side, the fold normally being compressibly closed elastically by said spring; whereby, upon a ring being forced into said fold, said packing will be forced into contact side against side of said fold through the ring by said springs.

LYMAN G. HUNTER.
